UNITED STATES PATENT OFFICE.

LESTER NEAL, OF PEORIA, ILLINOIS.

DOOR-HINGE.

1,330,647.

Specification of Letters Patent. Patented Feb. 10, 1920.

Application filed July 25, 1918. Serial No. 246,721.

To all whom it may concern:

Be it known that I, LESTER NEAL, a citizen of the United States, residing at Peoria, in the county of Peoria and State of Illinois, 5 have invented new and useful Improvements in Door-Hinges, of which the following is a specification.

This invention comprehends generally improvements in that class of inventions 10 known as builders' hardware, and more particularly relates to a door hinge.

This invention has for its principal object to provide a device of the above mentioned character designed for operably supporting a door so that the door will be normally maintained in a closed position without necessitating the requirement of additional spring means, et cetera, while at the same time the door may be readily swung 20 open in either direction, and subsequent to the release thereof will automatically return to a closed position.

More particularly the present invention may be said to consist of a pair of complementary members, one of which is designed 25 to be connected to the door frame, while the other is designed for connection to the door and is supported by the first member during swinging movement of the door.

It is a more specific object of this invention to construct each of the members with hinged knuckles, the adjacent faces of which are beveled correspondingly and positioned 30 so that they will normally intimately contact with each other for the maintenance of the door in a closed position, yet upon the swinging of the door one of these knuckles will ride upwardly on the other for permitting of the easy opening of the 35 door in either direction, while the parts are so related that subsequent to the releasing of the door they will, owing to the weight of the door, automatically return to an intimately contacting position, thus assuring 40 of the normal maintenance of the door in a closed position.

Among the other aims and objects of this invention may be recited the provision of a device of the character described with a view to compactness, and in which the number of parts are few, the construction simple and the cost of production low and the efficiency high.

Other objects as well as the nature, characteristic features and scope of this invention will be more readily apparent from

the following description taken in connection with the accompanying drawings and pointed out in the claim forming a part of this specification.

The invention is clearly illustrated in the accompanying drawings, in which:

Figure 1 is a side elevation partially in section showing the door in a closed position.

Fig. 2 is an elevational detail showing the hinge when the door is in an open position.

Fig. 3 is a perspective detail of the improved hinge.

Similar characters of reference are employed in all of the above described views, to indicate corresponding parts.

Referring now, more particularly, to the accompanying drawings there is illustrated a door frame 1 to which is swingably connected a door 2 by means of the improved hinges which are indicated in its entirety by the numeral 3.

In the present instance each hinge is composed of a pair of sections 4 and 5. Section 4 comprises a plate-like body portion 6 which is of a flat form and is designed to be attached to the inner side face of the door-frame by means of suitable fasteners 7, while formed integral with and vertically of the outer ends of the plate-like body 6 medially of the side edges thereof, is a hinged knuckle 8 of a cylindrical form, the upper edge of which is beveled downwardly from a point above the plate-like body 6 to a point on the opposite surface as indicated by the numeral 9, while embedded within and projecting centrally and upwardly from the upper beveled edge 9 of the knuckle 8 is a pintle 10. The other section 5 of the hinge consists of an attaching body 11 of a beveled conformation, the sides of which are positioned on opposite sides of the door, being straddled about the inner edge of the door and these sides are provided with openings 12 through which are engaged suitable fasteners 13 for the attaching of the section 5 in position on the door. The attaching body 11 has formed integral with the outer face of its intermediate portion and vertically thereof, another hinged knuckle 14 which is provided with a longitudinal bore 15 for rotatable disposition about the upright pintle 10, while the lower edge of this knuckle 14 is beveled as at 16 corresponding to the beveled upper end 9 of the knuckle 8. The bevel-

eled face 15 is inclined upwardly from a point beneath the intermediate portion of the attaching body to a point directly opposite the outer face of the knuckle and these 5 beveled edges intimately contact with each other under normal conditions for the maintenance of the door 2 in a closed position, yet the door may be easily swung in either direction causing the beveled face 15 to ride 10 on the beveled face 9, thus raising the knuckle 14 as well as the door for the opening thereof so that subsequent to the release of the door, owing to the weight thereof, the beveled face of the knuckle 14 15 will ride in a reverse direction on the beveled face 9 for assuring of the automatic closing of the door, as is apparent.

It will be observed that the plate-like body portion 6, simulates the attaching body 11, 20 and may be readily bent to the shape of the latter, or the latter flattened out to conform to the shape of the former. The attaching body can therefore be readily applied to gates of various thicknesses or flattened out 25 and attached on the edge of a very thick gate. The plate-like body 6 is susceptible of the same change of form adapting it to a thick or thin gate-post or to a round gate-post.

30 It is believed in view of the foregoing description that a further detailed description of the operation of the invention is entirely unnecessary. Likewise it is believed that the advantages of the invention will be 35 readily apparent. However, it is to be noted particularly that the upper edge of the frame should be spaced from the upper edge of the door to permit of upward movement of the door on the opening thereof. It 40 is also to be understood that this hinge can

of course be used for supporting gates and other forms of doors, et cetera, other than the form disclosed which is merely illustrated for indicating the advantages of the particular form of hinge.

45 It will be understood that the above description and accompanying drawings comprehend only the general and preferred embodiment of this invention and that various minor changes in detail of construction, 50 proportion and arrangement of the parts may be made within the scope of the appended claim and without sacrificing any of the advantages of this invention.

55 What is claimed is:—

A hinge of the kind described comprising a pair of sections for mounting on a gate and gate-post respectively, that section for mounting on the gate-post embodying a plate-like attaching body and a knuckle formed integral with the outer face thereof, the upper end of said knuckle being beveled from a point above the point of juncture of the knuckle with the plate downwardly to a point directly opposite said juncture point, 60 that section for mounting on the gate embodying an attaching element and a knuckle beveled on the lower end to conform to and engage the beveled end of the first said 65 knuckle, a pintle mounted in the first said knuckle and entering the last said knuckle so that the latter may turn on it as a pivot when the relative positions of the beveled ends of the two knuckles change for the purpose specified, the plate-like body and the attaching element being conformable to 70 the post and to the edge of the gate on which they are respectively attached.

75 In testimony whereof I affix my signature.
LESTER NEAL.
